UNITED STATES PATENT OFFICE.

JOHN WILLIAM STOLLE, OF ASHLAND, MAINE, ASSIGNOR OF ONE-HALF TO JOHN C. WRIGHT, OF ASHLAND, MAINE.

WHIFFLETREE, NECK YOKE, OR EVENER.

Application filed August 8, 1922. Serial No. 580,498.

To all whom it may concern:

Be it known that I, JOHN W. STOLLE, a citizen of the United States, residing at Ashland, in the county of Aroostook and State of Maine, have invented a new and useful Whiffletree, Neck Yoke, or Evener, of which the following is a specification.

This invention relates to unbreakable whiffletrees, neck yokes and eveners, and has for its object the provision of a wooden body member of the same shape and size as the ordinary wooden whiffletree, neck yoke or evener now in general use, but internally reinforced in such a manner that its resistance to breakage will be increased at least fourfold without adding appreciably to the weight.

The invention contemplates the employment of a longitudinal reinforcing rod extending throughout the whiffletree, neck yoke, or evener, with the ends of the rod projecting beyond the ends of the body member and provided with securing means bearing against the ends of the body member so as to serve the double purpose of resisting breakage of said body member and to hold in place the usual whiffletree hooks or trace ring cuffs.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:

Figure 1 is a longitudinal section of the improved whiffletree;

Figure 2 is an enlarged detail in section of one end of the whiffletree showing the manner of securing one end of the reinforcing rod to the end of the whiffletree;

Figure 3 is a plan view of the lock washer; and

Figure 4 is an end view of the spanner nut for securely locking the reinforcing rod in position on the end of the whiffletree.

Referring to the drawing, I have shown for the purpose of illustration only, a whiffletree reinforced by my improved

method, and in which 1 designates a body member made of some light material such as hard wood, and provided with a longitudinal bore, either at the center or between the center and the rear face, through which bore is forced an iron rod 2, having one end threaded as shown at 3, and extended beyond one end 13 of the whiffletree body to loosely receive a lock washer 4, and a spanner nut 5 adapted to be tightly screwed against the lock washer.

Upon the ends of the body member 1 are shrunk, in the usual manner, sleeves or cuffs 6 provided with projecting hooks 7 for the reception of the ends of the traces or chains of a harness. The ends of the body member 1 are tapered so that when the sleeves 6 are mounted on said ends, the outer faces of said sleeves will lie substantially flush with the outer face of the body member. Running transversely of each sleeve on its inner wall is a rib 8 adapted to be seated within a groove in the end of the body member to prevent turning of the sleeve.

The lock washer is circular in plan and of a diameter to not only fully cover one end 13 of the body member 1, when placed in face-to-face engagement with said end, but to engage the outer peripheral edge of the cuff on that end of the body member.

The washer is provided with a central perforation 9 of sufficient diameter to permit the threaded end 3 of the rod 2 to slide freely through the perforation.

The threaded end 3 of the rod 2 is provided with diametrically disposed grooves 10 in which slide the lugs 11 projecting inwardly from diametrically opposite points on the periphery of the perforation 9, and thus prevent rotation of the rod when it is desired to tighten the nut.

On the inner face of the washer 4 are integrally formed pointed lugs or teeth 12 adapted to find a seat in the end 13 of the body member 1 by driving the washer inwardly. In this way turning of the washer relative to the body member, when locked by the nut 5, is prevented.

The spanner nut 5 is provided with spaced perforations 14 adapted to receive a tool for turning said nut up tightly against the washer 4 thus bringing the rod 2 under the desired tension. The nut 5 is of substantially the same diameter as the washer 4.

The end of the rod 2, which is opposite to the end 13 of the body member 1, is provided with an integrally formed head or cap 15, with its inner face flat and in engagement with the adjacent end of the body member, while its outer face is rounded to correspond with the shape of the nut at the other end. The shape, however, is not material. The diameter of the head or cap is substantially equal to the outer diameter of the cuff 6 so that said cuff will be engaged by the head or cap to prevent endwise movement of the cuff from one end of the body member. The washer 4 similarly prevents endwise movement of the cuff at the other end of said member.

A clevis 16 is secured to the central portion and in embracing relation with the body member 1 to provide means for attaching said body to a vehicle.

The nut 5, washer 4, and the cap or head 15 are not only adapted to prevent loss of the cuffs from the ends of the body member 1, but by bearing rigidly against the ends of the body member will act as a resistance to produce tensile strain on the reinforcing rod 2 when a pull is exerted on the ends of the body member, and which tends to bend said body member. The material of the body member likewise cooperates with the rod 2 to resist bending of the whiffle-tree, evener or neck yoke, since the strain is directed away from the center and outwardly towards the ends of the body member. With this construction, it will be impossible to break the whiffle-tree crosswise until the spanner nut is stripped off, the cap broken off, or until the tensile strength of the iron rod is overcome.

The construction just described is equally applicable for reinforcing singletrees, doubletrees, eveners and neck yokes with the same result.

What is claimed is:—

1. A device of the class described, comprising a wooden body member, a metallic reinforcing rod running longitudinally through said body member from end to end, with its ends projecting beyond the ends of said body member, cuffs mounted on the ends of the body member, and means mounted on the ends of the rod and of such a diameter that said means bear against the ends of said body member and also overlapping the cuffs and holding them in po-

sition on the body member, said means being held from rotation independent of the body member, and also holding the rod from rotation.

2. A device of the class described, comprising a wooden body member, a metallic reinforcing rod running longitudinally through said body member, a head or cap formed on one end of the rod and of a diameter to bear against the entire end of the body member, the other end of said rod being threaded and projecting beyond the body member, a washer mounted on that end of the rod and provided with teeth to be driven into the body member, and of a diameter to bear against the entire end of the body member, means formed on the washer and rod to hold the rod from rotative movement, and a nut screwed on the threaded end of the rod and bearing against the washer for placing the rod under tension, and serving also to hold the teeth of the washer in engagement with the body member.

3. A device of the class described comprising a body member, a reinforcing rod running longitudinally through said body member and provided with a threaded end projecting beyond said body, with diametrically disposed grooves running longitudinally of the threaded end of said rod, cuffs on the ends of the body member and provided with hooks, a head or cap integrally formed on the one end of the rod and abutting an end of the body member and of a diameter to engage the cuff on said end of the body member, a lock washer provided with a central perforation adapted to receive the threaded end of the rod, lugs projecting inwardly from diametrically opposite points on the periphery of the perforation and slidable in the grooves on the threaded end of the rod, teeth projecting from the inner face of the washer adapted to engage the end of the body member, said lock washer being adapted to engage the cuff, and a nut engaging with the threaded end of the rod and bearing against the washer for rigidly locking the rod in position and preventing loss of the cuffs from said body member.

In testimony, that I claim the foregoing as my own, I have hereto affixed my signature.

JOHN WILLIAM STOLLE.
